UNITED STATES PATENT OFFICE.

ROXANNA A. NORTON, OF NEW YORK, N. Y.

CURTAIN DRAPER.

Application filed January 5, 1925. Serial No. 634.

To all whom it may concern:

Be it known that I, ROXANNA A. NORTON, a citizen of the United States, and a resident of the city of New York, borough of 5 Manhattan, in the county and State of New York, have invented a new and Improved Curtain Draper, of which the following is a full, clear, and exact description.

This invention relates to curtain drapers and more particularly to a device adapted to be secured to a window frame or adjacent support and over which curtains may be draped or hung in the event a full window opening is desired.

It is a well known fact that the proper positioning of curtains to hang them or position them out of the way at certain periods is a very real problem. For example, at night when it is desired to open the window, the curtains should be drawn aside, first, to allow full ventilation and, second, to prevent the curtains from flapping and becoming soiled. At other times, 25 when it is desired to wash the window or for any other reason the curtains should be drawn back, the ordinary methods employed are more or less injurious to the curtains and extremely unhandy.

It is, therefore, the purpose of my invention to provide a device or devices which can be conveniently attached to the window frame, which will be out of the way when not desired for use, and which can be readily 35 moved to operative position and remain in such position so as to permit the curtains to be swung back of them or draped thereon and properly held so as to give a full exposure to the window opening.

A further object is to provide a device of this character which can be manufactured and sold at a reasonably low price, which can be conveniently attached by any one of average intelligence, and which will most 45 efficiently perform the functions for which it is intended.

With these and other objects in view, the invention consists in certain novel features of construction and combinations and arrangements of parts, which will be more fully hereinafter described and pointed out in the claim.

In the accompanying drawings—

Figure 1 is a perspective view illustrating 55 my improved devices in operative position on a window frame;

Figure 2 is a perspective view of one of my improved devices showing the same in vertical or inoperative position;

Figure 3 is a perspective view of the device showing the same in horizontal or operative position.

1 represents a window frame, 2 the sashes therein and 3 the curtains, which are hung in any approved or ordinary manner. At 65 each side of the window frame I attach one of my improved curtain drapers, and as these devices are precisely alike, a description of one will apply alike to both.

My improved draper comprises two parts, 70 namely, a supporting bracket 4 and an arm 5. The bracket 4 constitutes a plate adapted to be secured to the edge of the window frame by screws 6 or other analogous securing devices, and is formed with a tongue 7 75 which is stamped from the material of the plate and laterally offset therefrom, as clearly shown in Figures 2 and 3.

At the rear edge of the plate, a laterally projecting lug 8 is formed on the plate 4 80 and is in alinement with the tongue 7.

The arm 5 is made with a longitudinal slot 9 receiving the tongue 7 and is also made at one end with a recess 10 adapted to receive the lug 8 when the arm is in 85 horizontal position, as indicated in Figure 3. The free end of the arm 5 is bent into general hook-shape, as indicated at 11, so as to prevent the accidental removal of the curtain 3 when positioned thereover.

In operation, when the curtains are hanging straight on the window frame, my improved devices are located as indicated in Figure 2 with the arm 5 hanging vertically opposite the window frame so as to be out 90 of sight and offer no unsightly appearance. When it is desired to drape the curtains back, the arm 5 is moved to a horizontal position by turning the same on the tongue 7 and is then given a slight rearward longitudinal movement to position the lug 8 in the recess 10, as indicated in Figure 3, to maintain the arm 5 in horizontal position. When the parts are thus positioned, the curtains can be swung backwardly over the 105 arms and draped thereover in any desired manner.

While I have illustrated what I believe is a preferred embodiment of my invention, it is obvious that various slight changes and alterations might be made in the general form of the parts described without depart-

ing from my invention, and hence I do not limit myself to the precise details set forth but consider myself at liberty to make such slight changes and alterations as fairly fall within the spirit and scope of the appended claim.

I claim:

A device of the character described, comprising two members, one member consisting 10 of a plate, a laterally offset integral forwardly projecting tongue stamped from the metal of the plate at the forward portion of the plate, a laterally projecting integral lug on the plate bent at right angles thereto 15 and located at the rear of the plate in horizontal alinement with said tongue, the other

member constituting an arm bent at its forward end laterally and then rearwardly, constituting a hook-shaped barrier to prevent the escape of the curtain over the free end 20 of the arm, and said arm also at its other end having a longitudinal slot therein receiving the tongue and having a recess in its extremity to receive the lug whereby when the arm is in engagement with the lug 25 it will be held in horizontal position, and when moved forwardly to free it from the lug can be swung downwardly on the tongue as a pivot, and can be uncoupled from the tongue by a lateral twisting movement.

ROXANNA A. NORTON.
